UNITED STATES PATENT OFFICE.

LE ROY A. CRUMLEY, OF NEW YORK, N. Y., ASSIGNOR TO HARRY M. FELTENSTEIN, OF NEW YORK, N. Y., DOING BUSINESS AS M. EISENBERG & SON.

DESIGN FOR A LIGHTING-FIXTURE BACKPLATE.

Application filed January 29, 1927. Serial No. 20,537. Term of patent 7 years.

To all whom it may concern:

Be it known that I, LE ROY A. CRUMLEY, a citizen of the United States, and a resident of New York, county of Bronx, and State of New York, have invented a new, original, and ornamental Design for a Lighting-Fixture Backplate, of which the following is a specification, reference being had to the accompanying drawing, forming a part thereof.

In the drawings:

Figure 1 is a front elevational view of the lighting fixture back plate; and

Figure 2 is a top plan view of the same.

I claim:

The ornamental design for a lighting fixture backplate, substantially as shown.

LE ROY A. CRUMLEY.
